FIGURE 1 is a perspective view of a housing for a measuring instrument showing my new design;
FIGURE 2 is an end elevational view thereof;
FIGURE 3 is a rear elevational view thereof; and
FIGURE 4 is an underplan view thereof.

The dominant features of the design reside in the portions shown in full lines.

The undisclosed end of the housing for a measuring instrument is substantially the same in appearance as the end shown in FIGURE 2.

I claim:

The ornamental design for a housing for a measuring instrument, substantially as shown and described.
